UNITED STATES PATENT OFFICE.

JULIAN G. SCHWAB, OF CINCINNATI, OHIO, ASSIGNOR TO A. G. SCHWAB & SONS, OF CINCINNATI, OHIO, A FIRM COMPOSED OF HERBERT C. SCHWAB LOUIS LANGE, AND JULIAN G. SCHWAB.

DESIGN FOR A RING.

Application filed June 16, 1928. Serial No. 27,169. Term of patent 7 years.

To all whom it may concern:

Be it known that I, JULIAN G. SCHWAB, a citizen of the United States of America, and a resident of Cincinnati, county of Hamilton, and State of Ohio, have invented a new, original, and ornamental Design for a Ring, of which the following is a specification, reference being made to the accompanying drawing, forming part thereof.

Fig. 1 is a perspective view of a ring showing my new design.

Fig. 2 is a side view of the ring shown in Fig. 1.

I claim:

The ornamental design for a ring as shown and described.

JULIAN G. SCHWAB.
